WILLIAM JULIUS PATAKY, OF BROOKLYN, NEW YORK

KEYLESS LOCK

Application filed December 17, 1930. Serial No. 502,921.

This invention relates to new and useful improvements in a keyless lock.

The invention has for an object the provision of a keyless lock which cannot be opened by feeling when the cutouts are in line with the bolt. Generally, keyless locks are constructed with bolts which may be slightly moved when the lock is in the closed condition and the combination moved very carefully so as to feel when the cutouts come in line with the bolt, and the lock may be opened without the operator knowing the combination. This invention proposes the provision of a plurality of blind cutouts in the combination so as to mislead attempts at feeling.

The invention has for a further object the provision of a keyless lock which is characterized by a plurality of lock rings with interengaging parts so that they may be readily stacked. This is of great convenience in changing the combination of the lock in that the lock rings interengage and can be held in stacked condition without much difficulty.

It is a still further object of this invention to provide a keyless lock which is characterized by a bolt bent into the shape of an inverted U with the arms of the bolt of different diameter so as to engage into the lock one way only and to double the possible combinations of the lock.

A still further object of this invention is to arrange the lock rings with circular ridges at their top ends engageable in corresponding recesses at the bottoms so as to prevent the insertion of a knife or tool between the rings for possible feeling of the cutouts.

A still further object of the invention is the provision in a keyless lock of means for preventing turning of the lock ring unless the bolt is completely in its locked place.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:—

Fig. 1 is a side elevational view of a lock constructed according to this invention.

Fig. 2 is a plan view of Fig. 1.

Fig. 3 is an enlarged sectional view taken on the line 3—3 of Fig. 2. 55

Fig. 4 is a perspective view of one of the lock rings.

Fig. 5 is a perspective view of a shank member used in the lock.

Fig. 6 is a fragmentary sectional view 60 taken on the line 6—6 of Fig. 5.

Fig. 7 is a view similar to Fig. 3, but illustrating a modified form of the device, and

Fig. 8 is a plan view of one of the lock rings used in Fig. 7. 65

The keyless lock has a shank member 10 with a bottom flange 11. A plurality of lock rings 12 are stacked one above the other and superimposed upon the flange 11 and rotatively mounted upon the shank 10. A 70 detachable cover 13 is mounted upon the top of the shank and overhangs the top lock ring 12 so as to prevent the removal of the lock rings. A bolt 14 is extended through the cover 13 and in between the shank member 75 10 and the lock rings 12.

The shank member 10 is circular in horizontal cross section. The lock rings 12 are formed with inwardly projecting top ledges 15. These ledges are turned down along the 80 outer corners so as to provide top ridges 16, and at the bottoms the rings are of such a diameter so as to fit upon the ridges 16. This is very clearly shown in Fig. 3 where the rings are shown interengaging each other. 85 It should be recognized that the ridges 16 serve to rotatively connect the rings with each other and to prevent the insertion of a knife or tool between the rings, and also to hold the rings in a stacked position, the 90 latter case being particularly true when the rings are removed from the shank. The cover 13 is recessed on its bottom side so as to receive the ridge 16 of the top ring 12.

The detachable cover 13 is in the form of 95 a disc which has a central downwardly projecting stem 17 threadedly engaging into the top of the shank 10. When the lock is in the closed position, the bolt 14 prevents rotation of the cover and holds the lock closed as a 100

complete unit. The bolt 14 is of inverted U shape. Each of the arms of the bolt is formed with a shoulder 18 for resting against the top of the cover 13. The arms of the bolt beneath the shoulder are of different diameters, as may be clearly seen in Fig. 3, so that the bolt can be placed only one way into the lock. The ledges 15 of each of the rings are formed with diametrically opposite cutouts 19 and 20 for receiving the arms of the bolt. These cutouts are of different size so as to correspond with the diameter of each arm, necessitating the correct positioning of the ring before the bolt can be withdrawn. This arrangement doubles the possible combination of the lock. The arms of the bolt are formed with cutouts 21 allowing the passage of the ledges 15 of the various rings. These cutouts are so spaced that when the bolt is completely within the lock and the rings 12 in place, the ledges of the rings will engage in the cutouts. A plurality of blind cutouts 22 are formed in the bottom face of the ledges 15 of the different rings so as to mislead persons attempting to open the lock by the feel system. Each of the rings 12 are graduated on their outer face with numerals from one to ten. For each one of these numerals, there should be one blind cutout 22 or one of the real cutouts as 19 or 20. A starting line 23 is formed upon the periphery of the flange 11 so that the rings may be placed relative to each other and in a certain position relative to the shank 10. The shank 10 is formed with longitudinal cutouts 24 and 25 for allowing the passage of the arms of the bolt 14. The bolt is so positioned that half of it lies within the cutouts 24 and 25, and the other half extends beneath the ledges 15 of the rings 12.

A means is provided for preventing turning of the locking rings 12 when the bolt 14 is not in its complete inner position. This means is of advantage in that it is impossible to hurriedly close the lock and close it incompletely by not inserting the bolt its full distance, and then turning the rings 12 so as to hold the bolt in the locked position. If not for this means, the number of possible combinations of the lock would be reduced if it were closed in a condition with the bolt partially extended.

The means mentioned in the previous paragraph comprises a longitudinal member 26 slidably mounted in a longitudinal slot 27 formed in the shank 10. The longitudinal member 26 extends the complete length of the shank and has its top and bottom ends 28 enlarged so as to limit possible motion laterally only. A spring 29 is mounted within the opening 27 and acts against the inner face of the member 26 for normally urging it outwards. The outer face of the member is formed with a plurality of vertically milled lines 30 engageable in corresponding

vertically milled lines 31 formed upon the inner diameter of the ledge 15. A bell crank 32 is pivotally mounted intermediate of its ends at 33 in a cavity within the flange 11 and has one of its arms extended adjacent the longitudinal member 26 and pivotally connected to it by a pintle pin 34. The other end of the bell crank extends through a cavity in the flange 11 and terminates in an end 35 at the bottom of the longitudinal slot 24.

When the bolt is completely within the lock, one of its arms depresses the end 35 of the bell crank to pivot the bell crank so as to move the member 26 inwards. Then the rings 12 are free to be rotated. In the event that the bolt is withdrawn or slightly extended, then the spring 29 is free to urge the member 26 outwards so that the millings 30 on the member engage the millings 31 on the ledges 15 and latch the rings against rotation.

The operation of the lock may be traced by assuming it in the condition shown in Fig. 3. In this condition the bolt 14 may be withdrawn, since all of the cutouts 19 and 20 of the different rings 12 are in line with the arms of the bolt 14. To lock the lock, it is merely necessary to rotate all of the rings 12 so that the ledges 15 ride into the cutouts 21 in the bolt. Now the bolt cannot be withdrawn. To open the lock, it is necessary to place the rings back into their initial position and this can be done by knowing the combination and setting the rings as directed by the numerals on their outer faces and by the indicating line 23.

When the rings have been set so that the bolt 14 is free, the latter element may be drawn out. In the event that the operator wishes to change the combination of the lock, he need only remove the detachable cover 13 when the bolt 14 is out and then slip all the rings 12 off as a complete unit in stacked position. Then the rings should be taken apart and their relative positions changed. For example, the bottom ring may be placed on the top, and some intermediate ring at the bottom. The cutouts 19 and 20 of the different rings are arranged adjacent different numerals on the peripheries of the rings and it will be recognized that such changes change the combination.

In the modified form of the device illustrated in Fig. 7, a means has been shown for holding the bolt of the lock in its opened condition. The bolt is indicated by reference numeral 37 and distinguishes from the bolt in the preferred form in that its top is bulged out and in that one of its arms, indicated by reference numeral 38, is longer than the other arm, indicated by numeral 39, and the longer arm is formed near its end with a peripheral groove 40 communicating with a longitudinal groove 41.

extending substantially the full length of the arm 38. A peg 42 projects from the cover 13 and engages in the longitudinal groove 41. This construction allows the bolt 5 to be drawn out until the groove 40 reaches the pin 42 and then the bolt may be swivelled around upon the arm 38. This constitutes the opened condition of the lock and there is no chance of losing the bolt.

10 In Figs. 7 and 8 also, a means is provided for holding the various lock rings 12 against free rotations so as to hold them as set. This is accomplished by forming a plurality of radial slots 43 in the top ridges of each of the lock rings, these slots being so spaced as to correspond with one indicating number on the periphery, so that for each indicating number there is a slot. One pin 44 projects from the bottom portion of each of the lock 15 rings and is adapted to engage in any one of the radial slots 43 of an adjacent lower lock ring. The cover 13 is also provided with a pin 44 which can extend into any one of the radial grooves 43 of the top lock ring.

20 The cover 13 is set at a distance from the bottom flange 11 so that a small space 45 exists between the bottom lock ring and the flange. A spring 46 is disposed between the flange 11 and the bottom lock ring 12 for 25 normally urging all of the lock rings upwards so that the top one engages against the cover 13. It is this spring which causes the space 45. The various lock rings are held against rotations in that the various 30 pins 44 engage in the grooves 43. In order to turn the lock rings for setting the combination, it is necessary to manually depress downwards on any of the lock rings so as to close the space 45 and open a corresponding 35 space between a pair of adjacent rings, which will disengage one of the pins 44 from its groove 43 and then one of the lock rings is free to be turned. When released, the spring 40 46 urges the parts back into their engaged 45 positions. While the spring 46 is shown at the bottom, the operation would not be changed at all if it were located at the top for urging all of the lock rings downwards and the pins 44 and the grooves 43 correspondingly changed to cause interengagement in the lowered positions of the rings. Then it would be necessary to raise the rings 50 for disengaging one of them so that it may be set.

55 It is of extreme advantage to hold the various lock rings against free rotations in that after the lock is opened the rings will maintain the combination without accidentally moving from their positions. This adds great convenience to the lock in that it may be closed without the necessity of first resetting the rings to their combination. In the form of the device illustrated in Figs. 1 to 6, as soon as the bolt 14 is lifted, the lock rings are locked against free rotation and we

have the same condition as far as this feature is concerned as we have in the form of the device illustrated in Figs. 7 and 8.

While I have illustrated and described my invention with some degree of particularity, I realize that in practice various alterations therein may be made. I therefore reserve the right and privilege of changing the form of the details of construction or otherwise altering the arrangement of the correlated parts without departing from the spirit or the scope of the appended claims.

Having thus described my invention, what I claim as new, and desire to secure by United States Letters Patent is:—

1. A keyless lock, comprising a shank member with a bottom flange, a plurality of lock rings superimposed on said flange and rotative on said shank, a detachable cover on said shank and over said rings, a bolt extended through said cover and between said shank member and lock rings, and means for holding the lock rings against free rotation to hold them as set comprising a plurality of radial grooves formed in each of the lock rings, pins on each lock ring engaging in radial grooves of adjacent lock rings, a pin on said cover engaging in a radial groove of the lock ring adjacent said cover, and resilient means for holding the lock rings against each other so that said pins engage in the grooves and allowing manual moving of the rings to disengage one of the pins from its groove to allow rotation to one ring at a time.

2. A keyless lock, comprising a shank member with a bottom flange, a plurality of lock rings superimposed on said flange and rotative on said shank, a detachable cover on said shank and over said rings, a bolt extended through said cover and between said shank member and lock rings, and means for holding the lock rings against free rotation to hold them as set comprising a plurality of radial grooves formed in each of the lock rings, pins on each lock ring engaging in radial grooves of adjacent lock rings, a pin on said cover engaging in a radial groove of the lock ring adjacent said cover, and resilient means for holding the lock rings against each other so that said pins engage in the grooves and allowing manual moving of the rings to disengage one of the pins from its groove to allow rotation to one ring at a time, comprising a spring coaxial on said shank member and acting between said bottom flange and the lowermost of said lock rings for urging all of the lock rings in one direction.

3. A keyless lock, comprising a shank member with a bottom flange, a plurality of lock rings superimposed on said flange and rotative on said shank, a detachable cover on said shank and over said rings, a bolt extended through said cover and between said shank member and lock rings, and means for holding them as set, comprising means for hold-

ing adjacent lock rings from relative turning and disengageable upon separate longitudinal displacement of the rings.

Signed at New York, in the county of New York and State of New York, this 28th day of November, A. D. 1930.
